Primary Examiner—Joel Sincavage*Attorney, Agent, or Firm*—McAndrews, Held & Malloy[57] **CLAIM**

The ornamental design for the low profile housing for a rotatable electrical plug, as shown and described.

DESCRIPTION

FIG. 1 is a bottom perspective view of a low profile housing for a rotatable electrical plug;

FIG. 2 is a top perspective view of the low profile housing of FIG. 1;

FIG. 3 is a top view of the low profile housing of FIG. 1;

FIG. 4 is a side view of the low profile housing of FIG. 1;

FIG. 5 is a bottom view of the low profile housing of FIG. 1;

FIG. 6 is front view of the low profile housing of FIG. 1; and,

FIG. 7 is a rear view of the low profile housing of FIG. 1.

The broken line showing is included for the purpose of illustrating environmental structure only and forms no part of the claimed design.
